CLAIM

The ornamental design for a spout for dispensing beverages, as shown and described.

DESCRIPTION

FIG. 1 is a left side perspective view of a spout for dispensing beverages showing my new design;

FIG. 2 is a right side elevational view thereof;

FIG. 3 is a top view thereof;

FIG. 4 is a front view thereof;

FIG. 5 is a rear view thereof; and,

FIG. 6 is a bottom view thereof.

The broken lines in the Figures designate features which form no part of the claimed design.
